C. H. MITCHELL

STRAIGHTEDGE DEVICE FOR USE IN TRIMMING SHEET MATERIAL

Filed Oct. 13, 1922

INVENTOR:
CLYDE H. MITCHELL.

BY Whiteley and Ruckman

ATTORNEYS.

UNITED STATES PATENT OFFICE.

CLYDE H. MITCHELL, OF MINNEAPOLIS, MINNESOTA.

STRAIGHTEDGE DEVICE FOR USE IN TRIMMING SHEET MATERIAL.

Application filed October 13, 1922. Serial No. 594,309.

To all whom it may concern:

Be it known that I, CLYDE H. MITCHELL, a citizen of the United States, residing at Minneapolis, in the county of Hennepin and State of Minnesota, have invented certain new and useful Improvements in Straight-edge Devices for Use in Trimming Sheet Material, of which the following is a specification.

10 My invention relates to straight edge devices for use in trimming sheet material. An object is to provide a device of this character by means of which wall paper, window shades and other sheet material can be 15 quickly and easily trimmed at the desired distance from the edge of the material by cutting along a perfectly straight line.

The full objects and advantages of my invention will appear in connection with the 20 detailed description, and the novel features of my inventive idea will be particularly pointed out in the claims.

In the accompanying drawings which illustrate the operation of my invention in one 25 form,—

Fig. 1 is a top plan view of the device. Fig. 2 is a view in vertical section on the line 2—2 of Fig. 1. Fig. 3 is a view in vertical section on the line 3—3 of Fig. 1. Fig. 30 4 is an edge view of a sheet of wall paper or other sheet material folded for cutting.

As shown in the drawings, I provide a support or base consisting of two members 10 and 12 which are secured together by 35 hinges 14, the two members being preferably of wood. Screws 16 secure a brass plate 18 to the upper front portion of the member 10, this plate constituting a surface upon which the cutting may be done. Secured to 40 the front edge of the member 10 is a strip 20 which extends slightly above the upper surface of this member and which constitutes an abutment with which the front edge of the material to be cut may be engaged. Screws 22 secure a pair of arms 24 to the lower front portion of the member 10. Attached by pivots 26 to the fronts of the arms 24 are arms 28, the outer portions 30 of which are bent at right angles and provided with teeth 32 which constitute racks. The portions 30 of the arms 28 extend slidably through sleeves 34 to which is secured a straight edge cutting guide 36. A rearwardly extending convex strip 38 is secured to the guide 36 and this strip carries bearings 40 in which a shaft 42 is rotatably mounted. Secured to the shaft 42 are a pair of pinions 44 which mesh with the rack teeth 32. Secured to the shaft 42 is a bevel gear 46 in mesh with a bevel gear 48 mounted for rotation on a channel member 50 secured to the strip 38. Secured to the gear 48 is a handle 52 by which it may be rotated.

The operation and advantages of my invention will be readily understood in connection with the foregoing description. The drawings illustrate the use of the device in connection with a sheet of wall paper P whose edge is to be cut on a straight line. This sheet of paper has been coated with paste on one side after which the end portions have been folded over so as to constitute the two folds F. In the use of the device, the support is placed on standards or horses and the two pivoted arms 28 are swung down on the pivots 26 to the position shown in dotted lines in Fig. 2 carrying with them the bar 36, the shaft 42 and the parts associated therewith. The paper to be cut is placed in proper position on the support and the arms 28 carrying the parts associated therewith are turned back upon the paper. The vertical portion of the bar 36 constitutes a guide or straight edge for a cutter and this guide can be moved toward or away from the strip 20 at the front of the support by operating the handle 52, said guide being maintained parallel to the strip 20. The amount of material trimmed off can thus be varied as desired. The trimming is performed by running any suitable cutter along the bar 36 as a straight edge. In Fig. 1 a cutter which may be used is designated by the character C. This cutter forms no part of the present invention and does not need to be described in detail. In hanging heavy wall paper or wall covering it is customary to butt the adjacent edges of the sheets instead of overlapping them on the wall, and it is particularly desirable in such case that the edges should be trimmed on a perfectly straight line in order that there may be no gaps between the edges of the paper when on the wall. It will be understood that my device may be used for trimming other material such as window shades. The device can be folded for car-

rying purposes since the support consists of two members hinged together.

I claim:

1. A straight edge device for use in trimming sheet material comprising a support, arms pivotally attached to the front of said support, rack teeth on said arms, a straight edge cutting guide, pinions carried by said guide and meshing with said rack teeth, and means for rotating said pinions to vary the distance of said guide from the front edge of said support while maintaining it parallel thereto.

2. A straight edge device for use in trimming sheet material comprising a support, arms pivotally attached to the front of said support, rack teeth on said arms, sleeves slidably mounted on said arms, a straight edge cutting guide attached to said sleeves, a shaft rotatably carried by said guide,

pinions secured to said shaft and meshing with said rack teeth, and means for rotating said shaft.

3. A straight edge device for use in trimming sheet material comprising a support, arms pivotally attached to the front of said support, rack teeth on said arms, sleeves slidably mounted on said arms, a straight edge cutting guide attached to said sleeves, a rearwardly extending convex strip secured to said guide, a shaft rotatably mounted on said strip, pinions secured to said shaft and meshing with said rack teeth, a bevel gear secured to said shaft, a second bevel gear carried by said strip, and a handle secured to said last mentioned gear for rotating the same.

In testimony whereof I hereunto affix my signature.

CLYDE H. MITCHELL.
